UNITED STATES PATENT OFFICE

JACQUES STANITZ AND GEORGE D. BOYER, OF WARREN, OHIO, ASSIGNORS TO THE YOUNGSTOWN PRESSED STEEL COMPANY, OF WARREN, OHIO, A CORPORATION OF OHIO

CORRUGATING APPARATUS

Application filed April 22, 1932. Serial No. 606,971.

This invention relates to improvements in corrugating apparatus and, more especially, such apparatus designed for producing corrugations, ribs or ridges in the side walls of relatively deep receptacles or containers, for example, cylindrical washing machine tubs made out of drawn sheet metal. Our invention may be employed in producing either straight or spiral corrugations, as herein-
10 after set forth.

Heretofore, considerable difficulty has been encountered in connection with the formation of corrugations in tubs of the kind referred to. Such apparatus has ordinarily employed a pair of dies, one being provided with projecting parts to form the corrugations. These projecting parts, being subjected to hard wear, have ordinarily had a short life or else have become deformed or 20 roughened, causing improper operation. By the use of our invention, these objections are overcome.

It may be stated, in general, that the principal feature of our invention is the provision in one of the dies of rotatable members adapted to form the corrugations referred to. These rotatable members, for example, may be spherical, roller-shaped, or the like.

30 Other features and advantages of our invention will appear more fully as we proceed with out specification.

In those forms of devices embodying the features of our invention shown in the accompanying drawings—

Figure 1 is a view in side elevation of a completed tub with vertical corrugations; Fig. 2 is a view taken as indicated by the line 2 of Fig. 3, showing the corrugating apparatus; Fig. 3 is a view taken as indicated by the line 3 of Fig. 2; Fig. 4 is a view taken as indicated by the line 4 of Fig. 2; Fig. 5 is a view taken as indicated by the line 5 of Fig. 4; Fig. 6 is a view similar to Fig. 1 40 showing spiral corrugations; Fig. 7 is a view taken as indicated by the line 7 of Fig. 8 showing the apparatus for forming spiral corrugations; Fig. 8 is a vertical sectional view of the apparatus for forming spiral corrugations; Fig. 9 is a view taken as indi-
45

cated by the line 9 of Fig. 8; Fig. 10 is a view similar to Fig. 4 showing a modified form; and Fig. 11 is a view similar to Fig. 5 showing the modification of Fig. 10.

As shown in the drawings, 10 indicates a 55 cylindrical relatively deep container, for example, a wash tub after the same has been provided with the vertical corrugations 11 in its side wall. These corrugations provide raised vertical ridges or ribs on the inner 60 wall of the tub.

The apparatus for forming the corrugations 11 comprise the male and female dies 14 and 15, respectively, which are axially 65 relatively movable. As here shown, the upper part of the female die 15 is provided with a removable ring 15^a held in position on the flange ring 15^b by the machine screws 16.

The female die, indicated in general by 70 15, is provided with protruding balls 17 adapted to form the corrugations 11 in the tub 10 as the same is forced downwardly into the female die by the male die 14. The male die or punch 14 is provided with co- 75 operating grooves 18 to accommodate the corrugations 11 as they are formed in the wall of the tub.

As here shown, the balls 17 rest on a supporting block 19 which may be in the form 80 of a ring mounted between the members 15^a and 15^b. This ring may be attached to the member 15^b by the machine screws 20.

On top of the ring 19 is a spacing ring 21 with curved notches 22 embracing the 85 balls 17 and spacing them properly.

In the modified form shown in Figs. 10 and 11, the rollers 117 are substituted for the balls 17. In other respects, the construction and operation are substantially the 90 same as above shown, the rollers 117 resting on a supporting block or ring 119 corresponding to the member 19 in the other form. As here shown, the rollers are suitably spaced by the ring 121 carrying the 95 spacing teeth 122 lying between the rollers 117. In the form of Figs. 10 and 11, 114 indicates the male die, 115 the female die, and 110 the tub.

In the form shown in Figs. 6, 7, 8 and 9, 100

we have shown the invention embodied in apparatus for forming spiral grooves instead of straight ones. In this form, the tub is indicated by 210 and the spiral corrugations therein by 211. The male die is indicated by 214 and the female die, by 215. The construction and operation are substantially the same as in the making of vertical corrugations, except that the two dies, instead of being only axially relatively movable, must also be rotatably relatively movable. To accomplish this, the die 214 is rotatably supported on the vertically movable head 214^a. The parts of the male die 214 and 214^a are joined in the following manner. A plug 214^b with a flange 214^c is threaded into the portion 214. The part 214^a is provided with a flange 214^d lying under the flange 214^c. A row of balls 214^e is provided between the parts 214^a and 214^c and another row of balls 214^f is provided between the parts 214^a and 214. These balls lie in suitable grooves or raceways in the adjacent parts and permit the part 214 to rotate with respect to part 214^a, the balls lessening friction between the parts and furnishing thrust bearings for the downward movement of the part 214 and also for its withdrawal from the female die.

Rotation of the part 214 with respect to the carrier 214^a is limited by the pin 214^g extending into an arcuate slot 214^h in the member 214^a. A spiral spring 214ⁱ may be provided to yieldingly retard rotation of the part 214.

In the form shown in Figs. 6, 7, 8 and 9, the member 214 is provided with spiral grooves 218 to accommodate the corrugations 211 as they are formed in the wall of the tub. These corrugations are formed by the protruding balls 217 in the female die which are supported in the same manner as the balls 17 above described. The balls 217

follow the spiral grooves 218 in the male die and form the corrugations 211 in the tub.

The balls 217 are supported in a manner similar to the balls 17 and such support need not be described in detail. It will suffice to say that the balls rest on a ring 219 similar to the ring 19 and are suitably spaced by a ring 221 similar to the ring 21.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as permissible, in view of the prior art.

What we regard as new, and desire to secure by Letters Patent, is:

1. Apparatus for fluting a closed-bottom sheet metal tub or the like, comprising a female die provided with a series of inwardly protruding rotatable spherical members; and a male die in the form of a plunger adapted to engage the bottom and side wall of a tub and thrust the same into the female die, said male die having a series of grooves adapted to register with the rotatable members in the female die and permit said members to roll portions of the side wall of said tub into the grooves.

2. Apparatus as specified in claim 1, in which the female die is of circular cross-section, the male die is anti-frictionally mounted for oscillation on an actuating ram, and said male die is provided with helical grooves adapted to oscillate said male die as it moves within the female die.

we have shown the invention embodied in apparatus for forming spiral grooves instead of straight ones. In this form, the tub is indicated by 210 and the spiral corrugations therein by 211. The male die is indicated by 214 and the female die, by 215. The construction and operation are substantially the same as in the making of vertical corrugations, except that the two dies, instead of being only axially relatively movable, must also be rotatably relatively movable. To accomplish this, the die 214 is rotatably supported on the vertically movable head 214^a. The parts of the male die 214 and 214^a are joined in the following manner. A plug 214^b with a flange 214^c is threaded into the portion 214. The part 214^a is provided with a flange 214^d lying under the flange 214^c. A row of balls 214^e is provided between the parts 214^a and 214^c and another row of balls 214^f is provided between the parts 214^a and 214. These balls lie in suitable grooves or raceways in the adjacent parts and permit the part 214 to rotate with respect to part 214^a, the balls lessening friction between the parts and furnishing thrust bearings for the downward movement of the part 214 and also for its withdrawal from the female die.

Rotation of the part 214 with respect to the carrier 214^a is limited by the pin 214^g extending into an arcuate slot 214^h in the member 214^a. A spiral spring 214ⁱ may be provided to yieldingly retard rotation of the part 214.

In the form shown in Figs. 6, 7, 8 and 9, the member 214 is provided with spiral grooves 218 to accommodate the corrugations 211 as they are formed in the wall of the tub. These corrugations are formed by the protruding balls 217 in the female die which are supported in the same manner as the balls 17 above described. The balls 217

follow the spiral grooves 218 in the male die and form the corrugations 211 in the tub.

The balls 217 are supported in a manner similar to the balls 17 and such support need not be described in detail. It will suffice to say that the balls rest on a ring 219 similar to the ring 19 and are suitably spaced by a ring 221 similar to the ring 21.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as permissible, in view of the prior art.

What we regard as new, and desire to secure by Letters Patent, is:

1. Apparatus for fluting a closed-bottom sheet metal tub or the like, comprising a female die provided with a series of inwardly protruding rotatable spherical members; and a male die in the form of a plunger adapted to engage the bottom and side wall of a tub and thrust the same into the female die, said male die having a series of grooves adapted to register with the rotatable members in the female die and permit said members to roll portions of the side wall of said tub into the grooves.

2. Apparatus as specified in claim 1, in which the female die is of circular cross-section, the male die is anti-frictionally mounted for oscillation on an actuating ram, and said male die is provided with helical grooves adapted to oscillate said male die as it moves within the female die.
